CLAIM

We claim the ornamental design for a baffle, as shown and described.

DESCRIPTION

FIG. 1 is a top perspective view of a baffle showing our new design;

FIG. 2 is a bottom perspective view thereof;

FIG. 3 is a top plan view thereof;

FIG. 4 is a bottom plan view thereof;

FIG. 5 is a side elevational view thereof;

FIG. 6 is a cross-sectional view across line 6-6 of FIG. 3; and,

FIG. 7 is a cross-sectional view across line 7-7 of FIG. 3. The broken lines shown in the drawings are for the purpose of illustrating portions of the baffle and form no part of the claimed design.
